ELECTRIC MEAT CUTTING MACHINE

William Lasar, Downey, Calif.

Application January 27, 1958, Serial No. 49,425

Term of patent 14 years

(Cl. D55—1)

Des. 183,459

PAGE 2

Fig. 3

Fig. 4

Figure 1 is a perspective view of an electric meat cutting machine showing my new design;

Figure 2 is a side elevational view of said machine;

Figure 3 is a top plan view of said machine; and

Figure 4 is a rear elevational view of said machine.

I claim:

The ornamental design of an electric meat cutting machine, substantially as shown.
